UNITED STATES PATENT OFFICE.

JAMES R. ALLGIRE, OF INDIANAPOLIS, INDIANA, ASSIGNOR TO CHARLES B. COWAN, OF CANAL WINCHESTER, OHIO.

MACHINE FOR FORMING, INSERTING, AND CLINCHING STAPLES.

SPECIFICATION forming part of Letters Patent No. 242,807, dated June 14, 1881.

Application filed June 22, 1880. (Model.)

To all whom it may concern:

Be it known that I, JAMES R. ALLGIRE, a citizen of the United States, residing at Indianapolis, in the county of Marion and State of Indiana, have invented a new and useful Machine for Feeding, Cutting, and Bending Wire into Staples, also for inserting the staples through material and clinching the same, of which the following is a specification.

My invention relates to improvements in staple making, driving, and clinching machines, in which the wire is fed to the gage, cut and bent into a staple, and the staple inserted through two or more thicknesses of material and clinched; and the objects of my improvements are, first, to provide a means of feeding wire to the gage; second, to provide means for holding the wire in the gage while being cut and bent; third, to provide a means for inserting the staple, when formed, through the material to be fastened together; fourth, to afford facilities for holding the material while the staple is being inserted; fifth, to provide a means for bending the ends of the staple and clinching the same after passing through the material to be fastened together; sixth, to provide a device whereby each of the above-enumerated operations and results takes place in alternate manner, one after the other, from the time the wire has first been started to the gage until the material has been fastened and released from the machine. I accomplish these objects by the mechanism illustrated in the accompanying drawings, of which there are two sheets, in which—

Figure 1 is a top view of the entire machine. Fig. 2 is a side elevation of the same. Fig. 3 is a front elevation of the same. Fig. 4 is a detached and enlarged detail view of the feed-40 ratchet and part of its operating mechanism. Fig. 5 is a side view of the staple formed by the apparatus. Fig. 6 is a front view of the stationary head with the cap removed. Fig. 7 is a vertical cross-section of the head. Fig. 8 is a plan view of the cap in front of the head. Fig. 9 is a perspective of the front spring and device for holding the wire in the gage during the act of bending the wire into a staple. Fig. 10 is an end view of the wire-guide, and Fig. 50 11 is a perspective view of the machine with the wire-spool removed.

Similar letters refer to similar parts throughout the several views.

The main frame of the device consists of the horizontal arm A, which is wide vertically and thin in cross-section, with a vertical slot, A⁴, extending through the same. This arm is also provided with broad and thin pivotal bearings, A² above, and A³ below, near the front end, for the purpose of hinging or pivoting thereto certain levers, which will be hereinafter described, and the extreme front end of the arm is provided with the rear part, P', of the stationary head, which will be hereinafter described. The rear end of the arm A is secured to the standard B, and the standard made fast to any desired post or stand, so that the arm A projects horizontally forward toward the operator.

On the upper edge of the arm A is a slide, B', having side plates, b b', which project downward a short distance on each side of the arm A, thus forming a guide for the slide. To one side of this slide B' is attached an arm, D, which projects downward to the bottom of the arm A, whose use will be described hereinafter. The front upper edges of the side pieces, b b', are beveled, as shown at a, Figs. 1 and 2, and between said beveled parts is secured a vertical plate, C, having a cam, C', on its upper edge, and a beveled cam, C², at its base. This vertical plate operates in the slot A⁴ of the arm A and moves forward and backward with the slide B'. The slide B' is provided with wrist-pins c c', to which power is applied in any ordinary manner, whereby a reciprocating motion is imparted to the slide.

To the broad pivotal bearing A², above the arm A, is pivoted, on each side, the slotted lever E⁷, by the pivot f², which is located slightly below the center of the pivotal plates E² E³, as shown in Fig. 2. The rear arm, E E', of this lever is slotted, as shown in Fig. 1, to permit the vertical plate C to move freely therein, and the extreme rear end of each part E E' is beveled, as shown at i, Fig. 2, for operating on the beveled part a of the slide B'. The other end of the pivoted lever E⁷ is provided with a head, E⁶, to the front face of which is attached the cross-plate E⁴ of the movable head. This plate E⁴ is notched out at its top to receive the hammer end G' of the lever-hammer G, and its front face is provided

with a vertical groove, in which is inserted a vertical slide, *h*, Figs. 2 and 3. This plate or head *E'* is also provided with a vertical recess, *g'*, midway of its height, to receive the coil push-spring *g* and hold said spring in position. The slide *h* is also provided with a corresponding hole to receive the spring. The plate *h* is free to be forced down by the hammer *G'*, and when the hammer is raised the spring *g* causes the plate *h* to follow the hammer-head up. Thus the hammer-head *G'* is always kept in contact with the upper end of the slide or staple-clinching plate *h*. The hammer *G'* forms the front end of the lever *G*, and said lever is provided with a broad, thin pivotal bearing midway of its length, which is inserted between the pivotal bearing *E² E³* of the lever *E'* and pivoted by the stud or screw *f'*. The lower side of the rear end of this lever *G* is beveled or curved, as at *G²*, to be operated by the cam *C'* of the reciprocating plate *C*, as will be hereinafter described.

The front end of the arm *A* is provided with the cross-plate *P'*, (shown more fully in Figs. 2, 3, 6, and 7.) This plate is also provided with a vertical groove extending from the top to the bottom of its front side, in which operates the vertical slide or staple-driver *P²*. The upper part of the plate *P'* is provided with vertical slots *p' p'*, one on each side, in which the front ends of the two levers, *F F'*, operate. These levers *F F'* are pivoted to each side of the arm *A* by a pivot-stud, *f*, and the rear upper edges of each lever are beveled, as at *e*, to be operated by the cam *i'* on the side plates, *b b'*, of the reciprocating slide *B'*, as will be hereinafter described. The staple-driver *P²* is a flat plate of steel, having its upper end square and a hole in its lower end to receive the end *M³* of its operating-lever *M*, said lever *M* being pivoted to the pivotal plate *A³* of the arm *A*, and its rear end provided with two operating-cams, one, *M²*, at the rear end, the other, *M'*, a little in front and above the cam *M²*, which are operated by the lower cam, *C²*, of the reciprocating standard *C* in an alternate manner, as will be hereinafter described.

The front plate, *P*, of the head is shown in Fig. 8. Its upper part is provided with slots *p p'*, corresponding to those in the part *P'*. The central bar between these slots is provided with the cross-slots *t t'*, which receive the L-shaped ends *v'* of the spring *v*. This spring *v* is made fast to the front side of the plate *P*, as shown in Figs. 3 and 7, with its bent ends *v'* in the slots *t t'* of the plate. This spring *v* is also provided with a stud or pin, *v²*, the end of which is rounded to fit into a corresponding countersink formed in the face of the staple-driver *P²*, as shown in Fig. 7, the operation of which will be hereinafter described. The faces of the plates *P* and *P'* are provided with a small cross-groove on one side, as shown at *y*, Fig. 6, to permit the wire to pass through over the cutting and bending arms *F F'*.

On one side of the arm *A* is secured another arm or bracket, *H*, which projects sidewise, on

which, near the head *P P'*, is secured the wire-guide *I I' I²*, shown more fully in Figs. 3 and 10. This wire-guide is provided with a hole, *u*, corresponding to the hole *y*, for guiding the wire to the gaging, cutting, and bending devices.

On the bracket *H* is mounted the shaft *K⁵*, the upper end of which is held in place by the bracket-bearing *K*. The shaft *K⁵* is provided near its lower end, below the bracket *H*, with a ratchet-wheel, *K'*, the teeth of which are of the proper length, so that by the pawl *K²*, arm *D²*, connecting-rod *D'*, and a single movement 80 of the reciprocating slide *B'*, the wire will be fed the proper distance to form a staple of the required size. The arm *D²* is made fast to the shaft *K⁵* or ratchet *K'*, and projects some distance toward the main arm *A* of the machine. The pawl *K²* is pivoted on top of the arm *D²*, and held in contact with the ratchet by the spring *K³*. The connecting-rod *D'* is pivoted at *n* to the arm *D²*, and its other end is provided with a slot, *e'*, in which operates 90 the stud *e* attached to the arm *D*. The backward motion of the rod *D'* is arrested by the stop-pin *c³*, which is inserted in or forms part of the arm *A* of the machine.

Near the upper end of the shaft *K⁵*, but below the bracket *K*, is secured the feed-wheel *J*, having a groove, *j*, Fig. 2, turned in its periphery to receive and guide the wire from the spool *L*. In front of this feed-roller *J* is another small roller, *J'*, pivoted to the adjustable arm *J²*, which is pivoted to the bracket *K*. This roller acts as a pressure-roller to hold the wire tightly against the feed-roller *J*. Below the arm *J²*, on the bracket *H*, is also pivoted another arm, *J³*. Its front end is bent upward 100 so as to extend to the top of the arm *J²*. This bent portion is provided with an **U**-shaped steel spring, one leg of which is made fast to the bent arm and the other leg resting against the edge of the lever *J²*, thus forming a tension-spring, *g*, to force the roller *J'* against the wire *d* in the groove *j* of the wheel *J*.

On the bracket *H* is also secured a cam-lever, *J⁵*, which, when in the position shown in Fig. 1, holds its arm *J³*, with its spring *J⁴*, in close contact with the arm *J²*, and when turned or moved forward toward the spring *J⁴* releases the pressure of the spring on the arm *J²*, and consequently the pressure on the wire *d*.

L is a spool mounted on a suitable standard for holding the wire that is to be fed, cut, and bent into staples.

Z is a spring for holding the front end of the lever *E'* up.

m m are springs for holding the rear ends of the levers *F F'* up, and *N* is a spring for holding the rear end of the lever *M* up, all arranged as shown in the drawings.

The operation of my improved device is as follows, to wit: The spool *L* is first filled with wire, and the wire inserted in the groove *j* of the wheel *J*, between said wheel and the tension-wheel *J'*. The wire is then inserted in the hole *u* of the guide *I I' I²* and conducted into

the hole or groove y of the head $P P'$. The lever J^5 is then thrown back into the position shown in Fig. 1, causing the cam at its end to press the arm J^3 sidewise, and forcing the spring J^4 in contact with the arm J^2 , thus forcing the roller J' against the wire d . The slide B' is then moved forward and back by hand until one staple has been formed, the operator having a number of blank trays or other articles that are to be secured together by the staples ready for fastening. The operator then places one of the articles to be secured by the staple, as shown at P^5 , Fig. 2, on the top of the head $P P'$, and the machine is set in motion. As the slide B' moves forward the beveled parts $a a$ of the sides $b b'$ raise the rear end, E' , of the lever E^7 , causing the head E^4 to come down on top of the article to be fastened, thus holding the material P^5 , as it were, in a vise. At the same time that the lever E^7 is being thus operated the stud e of the arm D slides along in the slot e' of the connecting-rod D' to the front end of the slot, and as the top surface of the slide B' slides forward under the end E' of the lever E^7 the stud e moves the rod D' forward, thus causing the arm D^2 of the ratchet-wheel K' also to move forward and the pawl K^2 to slip past the teeth of the ratchet-wheel.

30 When the cam i of the side pieces, $b b'$, of the slide B' comes in contact with the curved ends l of the cutting and bending levers $F F'$, said levers are forced down at their rear ends until the sides $b b'$ can slide over their top surfaces. As these levers $F F'$ are depressed at their rear ends, the front ends, which operate in the slots $p p'$ of the head-plates $P P'$, move upward, the outer edge of the lever F' cutting off the wire d at the side of the slot p' , Fig. 6, and the inner edges of the ends of both levers F and F' bend the ends of the wire thus cut. The central portion of the wire, after being cut, and during the act of bending the ends, is held against the under side of the projecting ends v' of the spring v until the wire is bent into a staple, as shown in Fig. 5, the elevated ends of the levers $F F'$ forming side walls to guide the staple in its upward motion. At this stage of the operation the slide B' advances until the cam C^2 , at the lower end of the vertical plate C , comes in contact with the end M^2 of the staple-driving lever M , causing said lever M to be slightly depressed and raising the front end, which carries the staple-driving slide P^2 up sufficiently far as to force the pin b^2 , Fig. 7, out of the countersink in the driver P^2 . This slight motion forces the bent ends v' of spring v out from above the bent staple, thus leaving said staple free to be driven upward through the articles to be secured. The further advance movement of the slide B' causes the cam C^2 , at the bottom of the vertical plate C , to come in contact with the cam M' of the lever M , thus forcing the lever M rapidly down at its back end, causing the front end to rise equally as rapidly, carrying with it the staple-driver P^2 , which forces

the staple up through the material P^5 into the lower end of the groove formed in the head E^4 , under the clinching device or plate h . At the same time the advance movement of the slide B' causes the upper cam, C' , of the vertical plate C to strike the curved end G^2 of the hammer-lever, forcing it up and the hammer G down, carrying with it the clinching device or slide-plate h , the lower end of which is curved, as in Fig. 3, thus bending and clinching the ends of the staple above the work. On the return or backward stroke of the slide B' the hammer-lever G is first released and the spring g causes its front end, G' , to rise up, and at the same time the spring g causes the clinching device or slide-plate h to follow the hammer up. The lever M is then released and its rear end raised up by the spring N , causing the front end to fall until the staple-driver is at its lowest point. The pin v^2 of the spring v then slips into the countersink formed in the driver P^2 , causing the bent end v' of the spring to move back in the slots $t t'$ over the wire d , the slide still moving back until the levers $F F'$ are released, when the springs m force the rear ends up and permit the front ends to fall below the wire-hole y of the head. At the same time the stud e strikes the rear end of the slot e' of the rod D' , carrying the rod back and moving the ratchet-wheel K , causing the feed-rollers $J J'$ to feed another length of wire across the head $P P'$, above the ends of the levers $F F'$, when the rear end of the rod D' strikes the stop C^3 and arrests the backward motion of the rod. During this back stroke, just after the stud e engages the rear end of the slot e' , and before the end of the rod D' strikes the stop, the lever E^7 is released from the inclined plane a of the sides $b b'$ of the slide, and as the rear end of the lever E^7 falls the front end is raised by the spring Z , and the material P^5 , which has been secured together by the staple, is released from the vise-jaws, after which the operation is repeated.

What I claim as new, and desire to secure by Letters Patent, is—

1. The combination, in a staple-forming, bending, and clinching machine, of the main arm A , having a vertical longitudinal slot, A^4 , and pivotal bearings $A^2 A^3$, the slide B' , having downward-projecting sides $b b'$, provided with a beveled front, a , and a cam, i' , the vertical bar or plate C , having the cam C' at its top and the cam C^2 at its bottom, the wire cutting and bending levers $F F'$, having their rear ends rounded or beveled, as at l , the lever E^7 , with beveled end i , the lever G , with beveled or rounded end G^2 , lever M , with its two cams, $M' M^2$, the arm D , with stud e , the connecting-rod D' , with slot e' , the lever D^2 , ratchet K , pawl K' , feed-wheel J , pressure-wheel J' , the head $P P'$, with slide P^2 , the spring v , with pin v^2 and L-shaped end v' , the head E^4 , with slide h , and spring g , all arranged and operated to advance the wire, cut it off, and bend, drive, and clinch the link, hold the work, and release the same after fastening, by a single forward and backward stroke of the

- slide mechanism, substantially as shown and described.
2. The combination of the slide B' and the side plates, b b', having beveled tops a and under-curved ends i', the vertical plate C, with cam C' at its top and cam C² at its base, and the downward-projecting arm D, substantially as described, for the purposes specified. 45
3. In combination with the vertical standard C, having a cam C' at its top, the hammer-lever G, pivoted to the lever E⁷, as described, for the purpose specified. 50
4. In combination with the side guides, b b', having the inclined parts a, and vertical plate C, having the cam C', the slide B', the lever E⁷, and hammer-lever G, substantially as shown and described. 55
5. The lever E⁷, having the end E⁶, provided with the head E⁴ and plate E⁵, and also having the clinching device h, with spring g, combined with the hammer-lever G G' G², substantially as shown and described. 60
6. The clinching-plate h, with spring g, combined with the head E⁴, and hammer G' of the lever G, as described, for the purpose specified. 65
7. In combination with the side guides, b b', of the slide B', having the under curved or beveled parts i', the cutting and bending levers F F', pivoted to the arm A, as shown and described. 70
8. In combination with the vertical plate C of the slide B', having the cam or inclined part C² at its lower end, the staple-driving lever M, with cams M' M², as and for the purpose specified. 75
9. The lever M, having two cams, M' M², at one end, operated by the cam C² at the end of the plate C of the slide B', and a small lug, M³, at its front end, combined with the staple-driver P² and spring v, as and for the purpose specified. 80
10. The spring v, having a forked L-shaped end, v', and a pin, v², combined with the staple-driver P², said staple-driver having a countersink for receiving and operating the pin v² 45
11. The lever M, with cam M², operated by the cam C² of the plate C of the slide B', combined with the staple-driver P², having a countersink in it, and the spring v, with pin v² to 50 fit in the countersink of the staple-driver, whereby the pin v² is pushed out of the countersink as the staple-driver moves up, and is inserted in the countersink as the driver moves down, for the purpose specified. 55
12. The lever M, with cam M', operated by the cam C² of the plate C of the slide B', combined with the staple-driver P², whereby the staple is driven upward through the material to be secured, as shown and described. 60
13. In combination, the levers F F', the lever M, the staple-driver P², and the spring v, with its L-shaped forked end v' and pin v² and head P P', with slots p p', whereby the wire for the staple is cut, bent, released by the forward movement of the spring v, and driven through the work by the driver, substantially as shown and described. 65
14. The pressure-roller J on the adjustable lever J², combined with the spring J⁴ on the L-shaped arm J², and the cam-lever J⁵, as and for the purpose specified. 70

In testimony whereof I have signed my name to this specification in the presence of two subscribing witnesses.
